UNITED STATES PATENT OFFICE

111,592

DESIGN FOR A WALL TELEPHONE SET

Morris Rose and Nils A. Judsen, Chicago, Ill., assignors to Kellogg Switchboard & Supply Company, Chicago, Ill., a corporation of Illinois

Application July 31, 1937, Serial No. 70,772

Term of patent 14 years

To all whom it may concern:

Be it known that we, Morris Rose and Nils A. Judsen, citizens of the United States of America and residents of Chicago, in the county of Cook and State of Illinois, have invented a new, original, and ornamental Design for a Wall Telephone Set, of which the following is a specification, reference being had to the accompanying drawing, forming a part thereof.

The figure is a perspective view of the wall telephone set showing our new design.

We claim:

The ornamental design for a wall telephone set, substantially as shown.

MORRIS ROSE.
NILS A. JUDSEN.
